UNITED STATES PATENT OFFICE.

PHILIP MUELLER, OF DECATUR, ILLINOIS.

FULLER BALL.

1,263,792.

Specification of Letters Patent. Patented Apr. 23, 1918.

Application filed March 24, 1916. Serial No. 86,506.

To all whom it may concern:

Be it known that I, PHILIP MUELLER, a citizen of the United States, residing at Decatur, in the county of Macon and State 5 of Illinois, have invented new and useful Improvements in Fuller Balls, of which the following is a specification.

This invention relates to Fuller balls, and has as its objects to retain the initial 10 resiliency and normal shape of the ball, to prevent deterioration and permanent distortion thereof, and generally to increase the efficiency and prolong the life of the Fuller ball.

When Fuller balls having no protecting jacket or shell are used, the elastic or rubber body portion becomes permanently distorted in shape due to continued pressure upon the same, the surface of the ball at 15 the valve seat end of the same becomes uneven which results in undue leakage, and the ball generally will give away or break down under the strain to which it is almost continually subjected. It has been proposed 20 to place a rigid or non-expansible metal shell or jacket about the elastic ball, but it has been found that the portion of the ball within the shell cannot expand radially to any appreciable extent, and, therefore, the 25 valve seat end or exposed portion of the ball must take up the entire strain and is forced to spread outwardly over the edge of the metal jacket or shell, with the result that the edges of the ball are soon cut and 30 the seating surface thereof is greatly impaired.

I overcome the above and other disadvantages of Fuller balls heretofore used by encircling or incasing the Fuller ball within 35 a shell or jacket, which jacket is slit adjacent the valve seat end of the elastic or rubber body permitting the rubber to be compressed to a greater distance throughout the length of the ball, aiding the ball to 40 assume its normal shape after the ball is moved from the valve seat, and prolonging the life of the ball materially.

The above and other objects of my invention are obtained by the structure described in the following specification, and illustrated in the accompanying drawings, it being understood, however, that the present embodiment of my invention is by way 45 of illustration, and that I do not wish to limit myself to the particular construction shown.

Referring to the drawings,—

Figure 1 is a longitudinal sectional view taken through a Fuller cock embodying my invention, the valve being closed. 60

Fig. 2 is a longitudinal section through the shank portion of the cock shown in Fig. 1, the Fuller ball being shown in elevation and the valve being open.

Fig. 3 is a perspective view of the several 65 parts of which my improved Fuller ball is constructed, the same being shown in disassembled relation.

Referring to the drawings wherein like numerals represent like parts in the several 70 views, 10 designates the body portion of the Fuller cock which may be of any suitable construction, the particular embodiment shown in the drawings being by way of illustration only. The Fuller cock, as is 75 usual, is provided with an eccentric stem 11 passing through the cap 12 and having a handle 13 on its outer end for operating the valve. Secured by means of screw-threads to the inlet of the cock is a tail 80 piece 14 in which the Fuller ball 15 reciprocates, the ball being carried by the valve stem 16 connected at its forward end to the crank end of the eccentric stem 11, as is usual. 85

In accordance with my invention the Fuller ball 15, which may be substantially in the form of a cylinder as shown, is encircled by a jacket or casing 17 which, in the present instance, comprises a cylindrical 90 member open at both of its ends, the edge of one of the ends being crimped inwardly to provide an internal bead or shoulder 24 which operates as a stop to prevent the split casing 17 from being pushed too far forward 95 upon the Fuller ball 15. The casing 17 is constructed of any suitable metal having the required resiliency, and the casing 17 together with the washer 18 forms what may be termed a shell which entirely incloses one 100 end of the ball. The end of the casing 17 terminates somewhat short of the valve seat end of the cylindrical rubber body 15 and is slit through a portion of its length as at 19, so as to provide a plurality of spring 105 fingers or sections 20. The casing 17 is retained in place on the ball 15 due to the frictional engagement therebetween and the resiliency of spring sections 20. In the present instance, I have shown the casing 17 as 110 having six slots and a corresponding number of spring sections, but it is, of course,

understood that the number of slots may be varied as desired, and that generally the construction of the casing may be varied so long as it allows the Fuller ball to expand 5 radially through a portion of its length, and aids the same to retain its normal shape.

The rubber cylinder or ball 15 and the washer 18 are centrally apertured to receive the reduced end of the valve stem 16, and a 10 nut 21 is screw-threaded on the inner end of the stem and forced against the washer 18 to retain the Fuller ball 15 against the stop or abutment 22 on the valve stem.

When the cock is operated to close the 15 valve, the rubber ball or cylinder 15 is brought into engagement with the seat 23, as shown in Fig. 1, and there is a tendency for the ball to spread outwardly or expand radially. The slotted portion of the protecting casing or shell expands radially to accommodate the expansion of the rubber ball and, of course, the radial expansion is greatest toward the valve seat end of the 20 Fuller ball, and thus the pressure or strain exerted upon the ball when the valve is closed 25 is properly distributed throughout the length of the ball, while, at the same time, the shell reinforces the rubber body and aids it to retain its normal shape and resiliency. As the 30 end of the casing toward the seat end of the ball is slotted, it expands co-extensively with the Fuller ball and thus the valve seat end of the latter cannot be forced to spread over the edge of the casing. The spring pressure 35 of the fingers 20 permits expansion of the ball 15 each time the valve is seated and at the same time aids in returning the ball to its normal shape or diameter each time the valve is moved from its seat and thus 40 the valve may set due to age without becoming enlarged at its end and the valve is still serviceable after this setting from age occurs.

What I claim is:—

- 45 1. An elastic Fuller ball having a radially expandible encircling member.
2. An elastic Fuller ball having a metallic encircling member adapted to expand radially.
- 50 3. An elastic Fuller ball having an encircling member adapted to expand radially, the degree of expansion varying inversely as the distance away from the valve seat end of the ball.
4. An elastic Fuller ball having a metallic encircling member slotted longitudinally to allow radial expansion thereof.
5. An elastic Fuller ball having a metallic

shell provided with a closed end and radially expandible sides to permit expansion of the ball.

6. An elastic Fuller ball having an encircling metallic casing slotted longitudinally at the valve seat end of the ball to permit the ball to expand radially. 65

7. An elastic Fuller ball having an encircling casing unbroken at the end of the ball opposite the valve seat end and slotted longitudinally toward the valve-seat end. 70

8. An elastic Fuller ball with an encircling casing unbroken and non-expandible at one end and having a plurality of fingers engaging the ball at the valve seat end and permitting radial expansion of said end. 75

9. In combination, an elastic Fuller ball, 75 a shell about one end thereof comprising a cylindrical member slotted at one end and having an inturned flange, and a washer at the end of the ball and within said cylindrical member. 80

10. In combination, an elastic Fuller ball, and a casing about one end thereof comprising a cylindrical member slotted at one end to provide spring fingers which permit radial expansion of the ball and aid in returning the ball to its normal shape, said casing being retained on the ball by friction therebetween. 85

11. In combination, a valve stem having an abutment thereon, an elastic Fuller ball 90 having a central bore adapted to receive said stem and bearing against said abutment, means for retaining the ball upon the stem, and a shell about one end of the Fuller ball and comprising a cylindrical member slotted 95 at one end to provide spring fingers which permit radial expansion of the ball when it is forced to its seat.

12. A cap for inclosing a portion of an elastic valve, said cap having spaces formed in its walls for permitting expansive action of the portion of said valve within the cap. 95

13. A cap closely inclosing the rear portion of an elastic valve and preventing abnormal swelling thereof and having spaces formed in its walls for permitting expansive action of the valve within the cap, except at the rear end thereof.

In testimony whereof I have hereunto set my hand in presence of two subscribing witnesses.

PHILIP MUELLER.
